United States Patent Office

Des. 194,096
Patented Nov. 20, 1962

194,096

RESTAURANT BUILDING

Philip J. Gordon, 419 Margaret St., Plattsburg, N.Y.

Filed Aug. 16, 1961, Ser. No. 66,374

Term of patent 14 years

(Cl. D13—1)

FIG. 1

FIG. 2

FIG. 1 is a side view in elevation of a restaurant building showing my new design;

FIG. 2 is a top plan view.

The other side of the design shown in FIGURE 1 is substantially the same as the side shown except for a conventional door replacing one of the windows.

I claim:

The ornamental design for a restaurant building, as shown and described.
